UNITED STATES PATENT OFFICE.

JOHN W. WHITLOCK, OF RISING SUN, INDIANA.

MECHANISM FOR WINDING PERFORATE SHEET-MUSIC.

No. 837,991.

Specification of Letters Patent.

Patented Dec. 11, 1906.

Application filed October 5, 1905. Serial No. 281,490.

To all whom it may concern:

Be it known that I, JOHN W. WHITLOCK, a citizen of the United States, residing at Rising Sun, in the county of Ohio and State of Indiana, have invented certain new and useful Improvements in Mechanism for Winding Perforate Sheet-Music, of which the following is a specification.

The present invention embodies improvements in mechanical musical instruments of the self-playing type which utilize a perforate music strip or sheet and winding mechanism therefor.

The invention resides particularly in the operating means provided for winding and unwinding the music-strip with regard to the rolls commonly provided to support the same.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a perspective view of a winding mechanism for perforate sheet-music embodying the invention. Fig. 2 is a front view thereof. Fig. 3 is a transverse section on the line $x-x$ of Fig. 2. Fig. 4 is a detail perspective view of the slipper-lever and parts moved thereby. Fig. 5 is a view at the left-hand end of the mechanism. Fig. 6 is a detail perspective view of an end portion of the tracker-bar, showing the guide and adjusting means. Fig. 7 is a detail section showing the means for longitudinally adjusting the unwinding-roll.

Corresponding and like parts are referred to in the following description and indicated in all the views of the drawings by the same reference characters.

The component parts of the mechanism may have any relative arrangement and be mounted in a framework of suitable construction, depending upon the character of the instrument to which the invention is adapted. The unwinding-roll is indicated 1, the music-roll at 2, and the tracker-bar at 3. These parts may be of any construction and usual

arrangement and are mounted in a framework comprising parallel bars 4 and 5 and connecting-bars 6 and 7. One journal of the unwinding-roll is provided with a gear-wheel 8, and the opposite journal has a set-screw 9 connected therewith, whereby said roll may be adjusted lengthwise to meet existing conditions, a jam-nut 10 serving to hold the set-screw and roll 1 in the adjusted position.

The tracker-bar 3 is adapted to be moved longitudinally in accordance with this invention and is directed in its movements by guide-pins 11, secured to opposite ends thereof and arranged to work in openings formed in the frame-bars 4 and 5. A set-screw 12, threaded into the bar 4, has engagement with the tracker-bar to effect positive shifting thereof, as may be required, a jam-nut 13, mounted upon said set-screw, holding it and the tracker-bar in the located position.

The music-roll 2 is provided with the perforate music-sheet 14, which in the operation of the instrument passes over the tracker-bar 3 and is wound upon the roll 1. The music-roll 2 is supported at its ends by means of the spring-actuated pin 15 and the journal 16, the latter interlocking with the roll 2 to effect a positive turning thereof when it is required to rewind the music-sheet thereon. A pinion 17 is loosely mounted upon the journal 16, and a drive-chain 18 or like means connects said pinion with a gear-wheel 19, secured to a shaft 20, to which movement is imparted from a convenient portion of the operating mechanism of the instrument. In the event of the part 18 being a sprocket-chain, the elements 17 and 19 will be provided with corresponding sprockets or teeth to make positive engagement with the links of the chain. A half-clutch 21 is mounted upon the journal 16 to turn therewith and to move toward and from the element 17, which latter is provided upon the face adjacent to the part 21 with a corresponding half-clutch, whereby upon interlocking of the two half-clutches the parts 17, 21, and 16 rotate in unison, so as to effect a turning of the roll 2 when it is required to rewind the music-sheet 14 thereon.

A shaft 22 is mounted in the bar 5 and in a companion bar 23 to have both a rotary and a longitudinal movement and has a pinion 24 fast therewith and adapted to be thrown into and out of gear with the teeth of the

gear-wheel 8. A shipper-lever 25, pivotally supported at a point between its ends, has positive engagement at opposite ends with, respectively, a collar 26, fast with shaft 5 22, and the half-clutch 21. An arm 27 projects from the shipper-lever 25 and extends within the path of an operating-lever 28, moved at proper intervals by the mechanism of the instrument embodying the invention. 10 A sprocket-chain 29 or like connection transmits motion from the shaft 20 to the shaft 22 by means of sprocket-wheels 30 and 31, fast to the said respective shafts. In practice the shaft 20 is continuously driven from the moving part of the operating mechanism in any convenient way, as by means of a drive-belt (not shown) passing around a cone-pulley 32, fast to the outer end of shaft 20. The motion imparted to shaft 20 is 15 transmitted to each of the sprocket-chains 18 and 29 and to the parts 17 and 31. In one position of the shipper-lever 25 the part 21 is in clutched engagement with the parts 17, thereby causing shaft 16 to rotate, and the shaft 22 is moved so as to disengage the 20 pinion 24 from the gear-wheel 8. Rotation of journals 16 causes a corresponding movement of the roll 2, whereby the music-sheet is unwound from roll 1 and wound upon the 25 said roll 2. When the shipper-lever 25 is moved to the other position, the pinion 24 is in meshing relation with the gear-wheel 8 and the part 21 is disengaged with the part 17. Hence movement is imparted only to the 30 unwinding-roll 1, said movement being comparatively slow by reason of the differences in the diameters of the parts 8 and 24 and 31 and 30. When the unwinding-roll is thrown out of action and the roll 2 is thrown into 35 gear, the speed of said roll 2 is comparatively high by reason of the large diameter of the part 19 and the small diameter of the part 17. Hence the music-sheet is rewound upon the roll 2 rapidly. It is proposed to actuate the 40 shipper member 25 automatically from a convenient portion of the actuating mechanism of the instrument, a suitable trip mechanism being provided and timed to operate at the end of each piece any number of pieces, as 45 50 may be desired.

Having thus described the invention, what is claimed as new is—

1. In winding mechanism for perforate sheet-music, the combination of a music-roll, an unwinding-roll, a journal for the 55 music-roll, a drive-shaft, a gear 8 fast to the unwinding-roll; a longitudinally movable pinion-shaft adjacent to said gear, a pinion 24 fast to said pinion-shaft and movable longitudinally therewith into and out of mesh 60 with the gear 8, connecting means between the drive and pinion shafts to effect simultaneous operation thereof, a clutch mounted on the journal of the music-roll and having a member fast thereto, connecting means between the loose clutch member and the drive-shaft, and a shipper-lever operatively connected with the pinion-shaft to effect longitudinal movement thereof and intermeshing of the gear 8 and pinion 24; and said shipper-lever being connected with the said loose 65 clutch member.
2. In winding mechanism for perforate sheet-music, the combination of an unwinding-roll, a music-roll, a gear 8 fixed for rotation with the unwinding-roll, a pinion-shaft adapted to receive both a rotary and a longitudinal movement, a pinion 24 fast to said shaft and longitudinally movable therewith into and out of mesh with the gear 8, a clutch 70 mounted on a journal of the music-roll and having one member loose, a drive-shaft, a sprocket-chain connecting the drive-shaft with the pinion-shaft, a second sprocket-chain connecting the drive-shaft with the 75 loose clutch member, and a shipper-lever pivoted between its ends, one end of the shipper-lever having connection with the loose clutch member and the opposite end having connection with the pinion-shaft to 80 effect unmeshing of the pinion 24 and the gear 8 simultaneously with the meshing of the two clutch members.

In testimony whereof I affix my signature in presence of two witnesses.

JOHN W. WHITLOCK. [L. s.]
